Hello L. Church

Inventor,
William Wurdack.
By Paul Bakerwell Atty.

UNITED STATES PATENT OFFICE.

WILLIAM WURDACK, OF ST. LOUIS, MISSOURI, ASSIGNOR TO FRANK ADAM ELECTRIC COMPANY, OF ST. LOUIS, MISSOURI, A CORPORATION OF MISSOURI.

ADJUSTABLE PANEL-BOARD SUPPORT.

1,012,957.

Specification of Letters Patent.

Patented Dec. 26, 1911.

Application filed December 13, 1910. Serial No. 597,139.

To all whom it may concern:

Be it known that I, WILLIAM WURDACK, a citizen of the United States, residing at St. Louis, Missouri, have invented a certain 5 new and useful Improvement in Adjustable Panel-Board Supports, of which the following is a full, clear, and exact description, such as will enable others skilled in the art to which it appertains to make and use the 10 same.

This invention relates to devices that are used for supporting panel boards, and is an improvement on the panel board supporting means described in United States Patent 15 No. 929,812, to F. B. Adam, dated August 3, 1909.

One object of my invention is to provide a panel board support of the type described in said Adam patent above referred to 20 which is so constructed that the inwardly and outwardly adjustable device which carries the panel board will also serve as a supporting means for the outside trim or finishing frame that surrounds the opening 25 in which the panel board is set.

Another object is to provide a panel board support of the type referred to in which the adjustable device that supports the panel board is provided with a part 30 that snugly embraces the corner of the panel board lining and to which said lining can be securely connected.

Another object is to provide a panel board supporting means which is so constructed that the panel board can be adjusted inwardly and outwardly relatively to the wall or partition in which it is set, and also adjusted vertically and horizontally so 35 as to line it up or arrange it in a perfectly 40 straight position. And still another object of my invention is to provide a panel board supporting device that comprises few parts and which can be adjusted easily.

Other objects and desirable features of 45 my invention will be hereinafter pointed out.

Figure 1 of the drawings is a horizontal sectional view of a panel board cabinet provided with panel board supports constructed 50 in accordance with my invention; Fig. 2 is a perspective view of one of my improved supports; Fig. 3 is a vertical sectional view taken on approximately the line 3—3 of Fig. 2; Fig. 4 is a horizontal sectional view

taken on approximately the line 4—4 of 55 Fig. 3.

Referring to the drawings which illustrate the preferred form of my invention, A designates a panel board cabinet of any preferred type arranged in an opening in a 60 wall or partition 1, and 2 designates a panel board arranged in a vertical position inside of said cabinet and provided with a lining 3 which projects outwardly so that its outer edge will bear against the inside face of 65 the trim or finishing frame 4 which surrounds the opening in the wall in which the cabinet A is set.

Supports 5 are arranged inside of the cabinet A at the four corners of the board, 70 and each of said supports is provided with a device 6 to which the panel board and the lining are connected, said devices being so constructed that they can be adjusted inwardly and outwardly relatively to the cabinet 75 A and thus bring the outer edge of the lining 3 flush with the outer face of the wall 1 in case the cabinet A is not set plumb with said wall. The supports 5 are also adjustably connected to the cabinet so that the 80 panel board can be adjusted horizontally and vertically so as to line up the panel board or arrange it in a perfectly straight position in case the cabinet A is set crooked. The means herein shown for retaining the supports 5 85 in position consists of caps 7 which bear upon flanges 5^a at the inner ends of the supports and clamp said flanges against the rear wall of the cabinet A, said caps being secured to the cabinet by means of screws 8 90 which pass through slots 5^b in the flanges 5^a of the supports.

The adjustable device 6 on each support 5 is provided with a portion to which the panel board is connected by means of screws 95 9 or other suitable fastening devices, and also an angle-shaped portion 10 which embraces the corner of the panel board lining and extends approximately the entire depth of said lining. The support 5 is substantially angle-shape in cross section so that the portion 10 of the adjustable device 6 will fit snugly inside of same, and said support 5 is provided with an elongated slot 5^c for receiving a bolt 11 or other suitable fastening device which is tapped into the angle-shaped part 10 of the panel board supporting device 6, a washer 12 being in-

terposed between the head of said bolt and the support 5 so as to cause the device 6 to be clamped tightly to the support when said bolt is tightened. The support 5 is provided with flanges 5^a that extend longitudinally of the slot 5^c, and the panel board supporting device 6 is provided with a guide lug 13 that lies between said side flanges and thus prevents the panel board supporting device 6 from twisting or turning relatively to the support.

In the preferred form of my invention as herein shown, the clamping bolt or screw 11 is tapped into the lug 13 of the adjustable panel board supporting device 6 but it will, of course, be obvious that said screw could be tapped into any other desired portion of said device.

Instead of connecting the outside trim or finishing frame 4 directly to the support 5, as in the structure described in said prior Adam patent, I have provided the adjustable panel board supporting device 6 with means to which said outside trim or finishing frame can be connected, said means preferably consisting of a lug 14 that projects laterally from the upper end of the angle-shaped part 10 of the device 6. The lug 14 is preferably arranged at the corner 30 of the angle-shaped portion 10 and is provided with an opening 15 for receiving a fastening device 16 which passes through the outside trim or finishing frame 4, but if desired, the portion 10 could be provided with a continuous flange or a plurality of lugs for securing the outside trim thereto.

One of the desirable features of a panel board mounting of the construction above described is that it enables the part to which the outside trim is connected to be adjusted inwardly and outwardly and thus arrange said part practically flush with or in parallel relation to the outside face of the wall in which the cabinet is set, it being of course understood that the adjustment of the panel board supporting device 6 longitudinally of the support 5 is effected by loosening the screw 11 and moving said device 6 to the proper position. Another desirable feature of a panel board mounting of this description is that it enables the panel board and the lining thereof to be adjusted horizontally and vertically so as to line it up or arrange it in a perfectly straight position in case the cabinet A is crooked; and still another desirable feature of such a structure is that each support 5 is retained in position by means of a single fastening device 8 which simply has to be loosened, but not removed, when it is desired to adjust the support to line up the panel-board.

The fact that the corners of the panel-board lining are snugly embraced by angle-shaped parts 10 to which the lining is securely connected by means of screws 3^a or

other suitable fastening devices, overcomes any tendency for the members which constitute the lining to pull apart or become displaced, and as the device consists of only two substantially angle-shaped metal members and suitable fastening devices for securing them together and to the supporting structure, the device is very strong and serviceable and can be manufactured at a low cost.

Having thus described my invention, what I claim as new and desire to secure by Letters Patent is:

1. A panel board support comprising means which is adapted to be connected to a stationary support, an adjustable panel board carrying device mounted in said means and adapted to be adjusted so as to move the panel board toward and away from said support, and means on said device for carrying the outside trim or finishing frame that surrounds the panel board opening.

2. A panel board supporting device comprising a member which is adapted to be connected to a supporting structure so as to sustain a vertically disposed panel board in operative position, and an adjustable part on said member to which the panel board and the outside trim or finishing frame can be connected, said part being adapted to be adjusted toward and away from the supporting structure to which said member is connected.

3. A panel board supporting means comprising a member which projects laterally from a supporting structure, a longitudinally adjustable part on said member to which the panel board is connected, and means on said adjustable part to which the outside trim or finishing frame can be connected.

4. In a panel board mounting, a part which projects laterally from a supporting structure, a longitudinally adjustable device mounted on said part and provided with portions to which the panel board and the panel board lining can be connected, and a lug on said adjustable device to which the outside trim or finishing frame is connected.

5. A panel board support comprising a substantially angle-shaped member which is adapted to project laterally from a supporting structure, a substantially angle-shaped part arranged in engagement with said member and provided with portions to which a panel board and an outside trim or finishing frame can be connected, and means for connecting said part to said member.

6. A panel board support consisting of a substantially angle-shaped member provided at its inner end with a flange which bears against a supporting structure, a panel board supporting device adjustably mount-

- ed on said member and provided with a substantially angle-shaped part which said member embraces, and a lug on said angle-shaped part to which an outside trim or finishing frame can be connected.
7. A panel board support consisting of a substantially angle-shaped member provided at its corner with an elongated slot and flanges which are arranged at the sides of said slot, a panel board supporting device arranged inside of said member and provided with a lug that fits between the flanges on said member, portions on said device to which the panel board lining and an outside trim can be connected, and a fastening device passing through the elongated slot in said member for securing said device in position.
8. A panel board support comprising a member that is adapted to be arranged at an angle to a supporting structure, a longitudinally adjustable panel board supporting device mounted on said member, a substantially angle-shaped part on said device which is adapted to embrace one corner of the panel board lining and to which the lining can be securely connected, and a lug on said angle-shaped part to which the outside trim or finishing frame can be connected.
9. In a structure of the character described, a panel board cabinet, adjustable members mounted on the rear wall of said cabinet and projecting forwardly therefrom, longitudinally adjustable devices mounted on said members for carrying the panel board and the panel board lining, and means on said devices to which the outside trim or finishing frame can be connected.
10. In a panel board mounting, a member arranged at an angle to a supporting structure, a clamp that retains said member in position and which is so constructed that said member can be adjusted in various positions on said supporting structure, and a longitudinally adjustable device on said member to which the panel board, the panel board lining and the outside trim are connected.
11. A panel board support comprising a substantially angle-shaped member provided at its inner end with a laterally projecting slotted flange, a clamping cap arranged in engagement with said flange, a fastening device for said cap that passes through the slot in said flange and projects into a stationary support, and a longitudinally adjustable device mounted on said member and provided with portions for carrying a panel board and also the outside trim or finishing frame which surrounds the panel board opening.

In testimony whereof I hereunto affix my signature in the presence of two witnesses, this eighth day of December 1910.

WILLIAM WURDACK.
